TREATMENT OF HYDROCARBON OIL

Jacque C. Morrell, Chicago, Ill., assignor, by
mesne assignments, to Universal Oil Products
Company, Chicago, Ill., a corporation of Del-
aware

Application February 16, 1931, Serial No. 516,271
Renewed June 14, 1938

6 Claims. (Cl. 196—48)

This invention relates to the treatment of hydrocarbon oil and more specifically refers to the conversion of higher boiling hydrocarbons into lower boiling hydrocarbons of a more valuable character.

In one of its specific aspects the invention relates to the conversion of hydrocarbon oils to produce thereby lower boiling hydrocarbons having higher anti-knock value when used as motor fuel than would normally be the case. More particularly the invention relates to the treatment of gasoline or products within the boiling range of gasoline to reform the same for the purpose of improving their anti-knock characteristics. Generally this comprises withdrawing separate fractions or cuts from the fractionator of a distillation system or of a cracking system and subjecting the cuts or fractions so withdrawn, either after combining the same or separately, to conversion conditions suitable for each individual cut or fraction to improve the anti-knock qualities of the fractions so withdrawn. This invention may apply to straight-run gasolines as separated by fractionation, or to cracked gasolines resulting from the conversion of higher into lower boiling hydrocarbons.

It has been found that motor fuels from various crude oils have pronounced knocking characteristics. Examples of these are Muskegon and various Pennsylvania crude oils. Analyses of the distillates within the boiling range of motor fuels from these crude oils show that the fractions possessing pronounced knocking properties may be distributed throughout the distillate, the distribution varying with the type and kind of crude oil. It is among the objects of this invention to separate and treat the components of hydrocarbon distillates showing pronounced knocking properties by segregating and subjecting the same to conversion conditions at elevated temperatures to improve their anti-knock characteristics.

In one specific embodiment the invention contemplates the provision of a process which comprises subjecting hydrocarbon oils to conversion conditions at elevated temperatures, discharging the heated hydrocarbons into a reaction chamber, removing the products therefrom and introducing the same into a vaporizer, separately withdrawing the unvaporized liquid residue and the vapors, subjecting the vapors to fractionation, separately withdrawing from the fractionator individual cuts or fractions to be combined for separate treatment under conversion conditions at elevated temperatures, or separately

treating the individual cuts or fractions so withdrawn under conversion conditions at elevated temperatures, cooling, condensing the vapors leaving the fractionator, and collecting the products therefrom.

In order to illustrate an operation of the process of the invention, reference is made to the accompanying diagrammatic drawing, which shows one form of apparatus suitable for carrying out the invention.

Raw oil charging stock is introduced through line 1 controlled by valve 2 and is pumped by means of pump 3 through line 4 through one or several paths. The oil may pass through line 5 controlled by valve 6 through heat exchanger 7 through line 8 controlled by valve 9 through line 10 controlled by valve 11 through line 12 into heating element 13 located in a suitable furnace 14, or the oil may be introduced directly from a feed line 5' into the fractionator 15, where it serves to cool the ascending vapors and is in turn pre-heated, combining with the reflux condensate formed by the fractionation of the vapors arising in the fractionator 15, and the combined feed is subsequently passed to the heating element 13 through line 16 controlled by valve 17 and through hot oil pump 18 into line 12 controlled by valve 12', or the raw oil charging stock may be passed directly to the heating element 13 through line 19 controlled by valve 20 and through line 10 in the manner heretofore described. The heated oil at conversion temperatures passes through line 15' controlled by valve 16' into the reaction chamber 17', the total contents of which are withdrawn through line 18' controlled by valve 19' into the vaporizer 20. The unvaporized liquid and vapors are separately withdrawn from the vaporizer 20'. The liquid is withdrawn through line 21, controlled by valve 22. The vapors pass through line 23 controlled by valve 24 and enter the fractionator 15, wherein they are subjected to fractionation. The reflux condensate is returned to the heating element 13 for reconversion as hereinbefore described. Fractionation may be assisted by the introduction of a suitable cooling liquid in fractionator 15, for example some of the distillate products of the process or other suitable cooling fluids. Side cuts or fractions are withdrawn from the decks or trays not shown, of fractionator 15 and introduced into separate reboiling systems or secondary fractionators 25, 25' and 25''. The liquid side cuts or fractions are withdrawn through lines 26, 26' and 26'', entering their respective

reboilers or secondary fractionating elements, being controlled respectively by valves 27, 27' and 27''. Steam or other heating medium may be introduced into the reboilers or secondary fractionating elements through line 28, 28' and 28'' controlled respectively by valves 29, 29' and 29''. The vapors leaving the reboilers pass back into the fractionator 15 through lines 30, 30' and 30'' controlled respectively by valves 31, 31' and 31''. The liquid withdrawn from the reboilers or secondary fractionators is passed through lines 32, 32' and 32'' controlled respectively by valves 33, 33' and 33'', or the liquid may be caused to by-pass the reboilers by passing through lines 34, 34' and 34'' controlled respectively by valves 35, 35' and 35''. In either event, all of the liquid may be combined by passing the separate cuts or fractions through lines 36, 36' and 36'' controlled respectively by valves 37, 37' and 37'', combining the same in line 38, from where it is withdrawn by means of pump 39 and passed through line 40 controlled by valve 41 into the heating element 42 located in furnace 42', where it is subjected preferably to high temperature conversion conditions to effect the maximum conversion into anti-knock components. All or a portion of each of the separate streams, or the combination thereof, may be passed through lines 43, 43' and 43'' controlled respectively by valves 44, 44' and 44'' and pumped by means of pump 45 through line 79 controlled by valve 80 into line 16 and from there through pump 18 line 12 and valve 12' into heating element 13: or the individual cuts or fractions from the reboiler or secondary fractionating elements, or direct from the decks or trays of the fractionator 15, may be introduced into the corresponding and respective heating elements 46, 46' and 46'' located respectively in suitable furnaces 47, 47' and 47'' through lines 48, 48' and 48'' controlled by valves 81, 81' and 81'' respectively to be subjected therein to conversion conditions, preferably at high temperatures, to effect maximum conversion into products of high anti-knock value. The heated hydrocarbons leaving the heating element 42 pass through line 49 controlled by valves 50 and 51 into the transfer line 15', or directly into the reaction chamber 17', or in the event that it is desired to operate heating element 42 at a pressure lower than that existing in the heating element 13 and/or reaction chamber 17' the heated hydrocarbons leaving the heating element 42 are by-passed through line 52 controlled by valve 53 by means of pump 54, wherein the pressure is raised, and through line 55 controlled by valve 60 and through line 49, in the manner hereinbefore described. Similarly, the heated hydrocarbons leaving the heating elements 46, 46' and 46'' pass through lines 61, 61' and 62'' controlled respectively by valves 62, 62' and 62'' and through line 63 controlled by valve 64 into the transfer line 15' or directly into the reaction chamber 17'. In some cases it may be desirable to introduce the vapors from the heating element 42 or the heating elements 46, 46' and 46'' directly into the vaporizer 20, particularly when it is desired to reduce the hydrocarbons treated to coke and distillate by what is commonly termed the "non-residuum operation." In this case the heated hydrocarbons leaving the heating element 42 are passed through line 49 in the manner previously de-

scribed and through line 66 controlled by valve 65 into line 18', or preferably directly into the vaporizing drum or chamber 20'. Similarly, the heated hydrocarbons leaving heating elements 46, 46' and 46'' pass through line 63 and through line 67 controlled by valve 68 into line 18', or preferably directly into the vaporizing drum or chamber 20'. The highly heated vapors assist in vaporizing the liquid in the vaporizing chamber 20 not only by virtue of the heat contained in the vapors but also the partial pressure of the vapors which reduces the average boiling point of the liquid within the vaporizing chamber. A plurality of vaporizing chambers is desirable in operations of this kind, permitting the accumulation of coke in one while the others are being cleaned or otherwise prepared for cutting into the system without interrupting the operation of the process and permitting continued operation over long periods of time. 20

The vapors leaving the fractionator 15 pass through line 69, controlled by valve 10, through cooler and condenser 71, line 72, controlled by valve 73, the condensed liquid being collected in receiver 74, from which it is withdrawn through line 75, controlled by valve 76. The gases are withdrawn from the receiver through line 77, controlled by valve 78, which valve may also serve to control pressure on all or part of the system. 30

The operating conditions employed may vary over a wide range, depending upon the type of charging stock treated and the results desired. Uniform pressures or differential pressures varying from atmospheric to high superatmospheric may be employed. Pressures varying from atmospheric to 2000 pounds per square inch, more or less, are suitable. Temperatures within the cracking range are employed; for example, from 800 to 1200° F., more or less. The high temperatures are suitable when gas-making is one of the objects of the process. Preferably, the heating element 13 is operated at relatively low temperatures with respect to the other heating elements 42, 46, 46' and 46'', the latter being operated at temperatures normally considered within the vapor phase cracking range, which is in excess usually of 1000° F., although any suitable cracking temperatures may be employed. 40

It is to be understood that the invention is not limited to the treatment described, as the principles and concepts of the invention permit of a very broad application. For example, if it is desired to improve the anti-knock value or knock-rating of gasolines containing fractions or components of markedly low anti-knock value, such as Pennsylvania straight run gasoline or gasoline from Muskegon crude oil or similar gasolines, these may be separated and segregated and separately treated. As an example of the relationship between the knock-rating and the boiling range of a straight run Pennsylvania gasoline, the following data is given: 50

	°F. Initial—110	Benzol equivalent
110		-0.2
110-202		+10
202-213		-0.2
235-240		-16.5
240-270		-0.2
270-300		+17
330-355		+35
355-400		26

Similarly, the gasoline from a Muskegon crude oil showed the following properties:

	Percent of crude	E. P. gasoline	Percent benzol
	7.0	290	+25.0
	9.0	300	+22.5
	11.5	310	+21.0
10	14.0	320	+19.0
	16.0	330	+16.5
	18.5	340	+13.5
	20.5	350	+10.0
	23.0	360	+5.0
	25.5	370	-1.5
	27.5	380	-12.5
15	30.0	390	-25.0
	32.5	400	-32.0
	35.0	410	-34.5
	37.0	420	-36.0
	39.5	430	-36.5
	40.5	437	-37.0

20 In the first set of data the anti-knock value of the individual fractions are given; in the second set the benzol equivalent, which indicates the anti-knock value equal to a blend of 25 Pennsylvania straight run gasoline and benzol containing the indicated percentages of the latter, is based on the composite of the given fraction with all the fractions preceding.

It is clearly evident, however, that by suitable 30 fractionation of the gasolines various fractions or cuts may be removed and subsequently subjected to retreatment according to the principles of the present invention to increase the anti-knock value thereof.

35 As a specific example of results obtained by the operation of my invention a Muskegon crude oil is treated by the method described. The low boiling components of the crude oil are separated into the fractionating column and the separate cuts are withdrawn, particularly those which are low in anti-known value. From the specific example given above, it is evident that the fraction boiling above 360° F. to 437° F., may be withdrawn and combined for a single separate treatment or subjected to separate treatment in several cuts 40 or fractions. The fractions withdrawn in the case under consideration consist not only of the straight run naphtha but also contain the intermediate boiling cracked products, some of which likewise have poor anti-knock value. Two such 45 fractions are separately treated, one being heated in the separate heating elements to a temperature of 975° F. and that having the lower anti-knock value of the two is heated to a temperature of approximately 1050° F. The conditions 50 of treatment in the main heating element corresponding to 13 wherein are treated the unvaporized material leaving the bottom of the fractionator 15, together with reflux condensate withdrawn therefrom, are approximately 920° F. and about 200 pounds pressure per square inch. The pressure in the reaction chamber 17' is approximately 200 pounds per square inch also. The pressure in the heating elements in which the two side cuts are treated is likewise approximately 200 pounds per square inch. The pressure 55 in the vaporizer, fractionator, condenser and receiver is approximately 30 pounds per square inch, the elements succeeding the fractionator being equalized in pressure with the fractionator. 60 When the oil is treated without reconversion of the side cuts withdrawn from the fractionator 15, the anti-knock value of the motor fuel produced thereby is approximately 25 benzol equivalent. However, when treated in the man-

ner described the anti-knock value may be increased to 55% benzol equivalent.

In another case a Pennsylvania 40-44° A. P. I. distillate is treated. Approximately 60% of the low boiling product of the process is withdrawn 5 directly from the fractionator as side cuts and subjected to retreatment in a separate heating coil. The total yield of gasoline is approximately 68%, making a total of approximately 40% of the charging stock withdrawn as a side cut. The 10 side cut is subjected to a temperature of approximately 1000° F., the main charge being introduced directly into the heating element corresponding to 13, which is heated to a temperature of approximately 930° F. The pressure on the 15 heating element 13 is approximately 300 pounds per square inch and a similar pressure is maintained in reaction chamber 17'. The pressure on the heating element 42, wherein the side cut is reconverted, is about 200 pounds per square 20 inch. The pressure upon the vaporizing chamber, fractionator, condenser and receiver is approximately 30 pounds per square inch, allowing for pressure drops through that part of the system, whereas the product would normally have an 25 anti-knock value of approximately 40% benzol equivalent, were the side cut not treated, a product having an anti-known value of approximately 65% benzol equivalent can be obtained when the process is operated in the manner described. 30

In both cases the boiling range of the product is substantially improved, particularly the intermediate boiling points are lowered, as well as a large improvement in anti-knock value.

The yields of gasoline are not substantially 35 decreased, although some decrease is noted, but this slight disadvantage is greatly offset by the very marked increase in anti-knock value of the gasoline, which in some cases is rendered marketable and in other cases serves as a valuable 40 blending agent in improving the anti-knock value of the motor fuels otherwise deficient in this desirable property.

The examples are illustrative only of some of the broad possibilities of the invention.

I claim as my invention:

1. A process for producing anti-knock motor fuel from crude oil containing gasoline which comprises introducing the crude into a fractionating zone and contacting the same therein with cracked vapors formed as hereinafter set forth thereby vaporizing the gasoline from the crude and forming a mixture of unvaporized crude and reflux condensate separated from the cracked vapors, condensing the heavier portion of the gasoline from the commingled crude oil vapors and uncondensed cracked vapors while retaining the lighter portion of the gasoline in vaporous form, heating said mixture of unvaporized crude and reflux condensate to cracking temperature, independently heating said heavier portion of the gasoline to a higher cracking temperature adequate to increase its anti-knock value and then commingling the same with said mixture, separating the thus commingled oils into vaporous and residual products, supplying such separated vaporous products to the fractionating zone as said cracked vapors, and finally condensing and collecting said lighter portion of the gasoline uncondensed by the fractionation. 55

2. A process for producing anti-knock motor fuel which comprises fractionating crude petroleum oil together with cracked products and separating from the crude oil and cracked products a gasoline fraction of satisfactory anti-knock 75

value, a fraction containing natural and cracked gasoline hydrocarbons of inferior anti-knock value and a fraction heavier than gasoline, recovering the first-mentioned fraction, supplying the last-mentioned fraction to a heating zone and heating the same therein to cracking temperature under pressure, subjecting the second-mentioned fraction in a second heating zone to conversion conditions of temperature and pressure adequate to increase the anti-knock value of the gasoline hydrocarbons contained therein, and supplying resultant conversion products from said second heating zone and cracked products from the first-mentioned heating zone to said fractionating step.

3. A process for producing anti-knock motor fuel which comprises removing cracked vapors from an enlarged zone and fractionating the same in a fractionating zone in direct contact with crude oil containing natural gasoline thereby vaporizing gasoline from the crude and condensing fractions of the vapors heavier than gasoline, passing liquid products heavier than gasoline from the fractionating zone through a heating zone wherein they are heated to cracking temperature under pressure and subsequently discharging the same into said enlarged zone, removing gasoline-containing distillate from the fractionating zone and passing a portion of the gasoline hydrocarbons, including the low anti-knock constituents of the natural gasoline and the cracked gasoline, through a second heating zone, heating such gasoline hydrocarbons in the second heating zone sufficiently to increase the anti-knock value of the low anti-knock constituents thereof, discharging the thus heated hydrocarbons into said enlarged zone, and recovering the remaining portion of said gasoline-containing distillate removed from the fractionating zone.

4. A process of hydrocarbon oil conversion which comprises subjecting a crude oil containing gasoline to distillation temperature sufficient to vaporize the gasoline and separating the gaso-

line from the crude, passing portions of the crude heavier than gasoline through a heating zone and heating the same therein to cracking temperature under pressure, simultaneously passing gasoline boiling range hydrocarbons separated from the crude through a second heating zone maintained at higher cracking temperature than the first named heating zone and heating the same therein sufficiently to enhance the anti-knock value thereof, commingling vaporous conversion products of said portions of the crude and of said gasoline boiling range hydrocarbons and fractionating and condensing the commingled vapors.

5. The process as defined in claim 4 further characterized in that the gasoline vaporized from the crude is separated into a light fraction and a heavy fraction, the light gasoline fraction being recovered without subjection to cracking conditions and the heavy fraction being supplied to the second heating zone as said gasoline boiling range hydrocarbons.

6. A process of hydrocarbon oil conversion which comprises subjecting a crude oil containing gasoline to distillation temperature sufficient to vaporize the gasoline and separating the gasoline from the crude, passing portions of the crude heavier than gasoline through a heating zone and heating the same therein to cracking temperature under pressure, separating the gasoline vaporized from the crude into a light fraction and a heavy fraction and recovering the former, passing the heavy gasoline fraction through a second heating zone maintained at higher cracking temperature than the first-named heating zone and heating the same therein sufficiently to enhance the anti-knock value thereof, commingling the heated products from said heating zones and separating the same in an enlarged separating zone into vapors and residue, and fractionating and condensing the separated vapors.

JACQUE C. MORRELL.
